PLAIT FOR SPORT COATS AND THE LIKE

Reuben Karasic, Asbury Park, N. J.

Application February 10, 1934, Serial No. 710,586

8 Claims.

This invention relates to new and useful improvements in a plait construction for sport coats, garments and the like.

This invention relates to similar subject matter contained in my patent application Serial No. 669,482 filed on May 5, 1933, and entitled Plaits for sport coats and the like.

This invention has for an object the construction of a plait which is characterized by sheet material formed into a plait extending the entire width thereof, and a resilient frame associated with the bends of said plait for normally urging the plait into a closed position.

More particularly an arrangement is proposed wherein the resilient frame comprises spaced parallel flexible members held in spaced positions by elements connecting the ends thereof.

Still further the invention proposes a neat and efficient manner of sewing portions of the sheet material for the purpose of holding the resilient frame in position.

As another object of this invention an arrangement is proposed for the sheet material so that the frame may have one of the parallel flexible members extended through one of the bends of the plait and the other extended through the other bend of the plait.

Still further this invention proposes teaching the placing of plaits with the resilient frames and opposed to each other so as to form a double plait having a combined action similar to the single plait previously mentioned.

Furthermore as another object of this invention an arrangement is proposed for making the elements connecting the parallel flexible members adjustable to adapt the frame to plaits of different sizes.

Still further the invention proposes the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a fragmentary front elevational view of a piece of sheet material with a plait according to this invention.

Fig. 2 is a horizontal sectional view taken on the line 2—2 of Fig. 1.

Fig. 3 is a plan view of Fig. 1 but illustrated

without the holding stitches, and with the parts separated so that the interior construction may be seen.

Fig. 4 is a fragmentary sectional view taken on the line 4—4 of Fig. 3.

Fig. 5 is a perspective view of the resilient frame, per se.

Fig. 6 is a front elevational view similar to Fig. 1 but illustrating a double plait constructed according to this same invention.

Fig. 7 is a horizontal sectional view taken on the line 7—7 of Fig. 6.

Fig. 8 is a perspective view of a resilient frame constructed according to a modification of this invention.

Fig. 9 is a rear view of a sport coat in which the plaits are constructed according to this invention.

The plait construction shown in Figs. 1—5 inclusive, comprises sheet material 10 formed with a plait extending the entire width thereof and consisting of a front layer 11 continuing with a bend 12 extending the entire width to an intermediate layer 13 continuing with another bend 14 also extending the entire width of the material 10 to a rear layer 15. A line of stitches 16 secure the front layer 11 and the intermediate layer 13 together near the bend 12 forming a passage 17. Another line of stitches 18 secure the intermediate layer 13 and the rear layer 15 together near the bend 14 forming another passage 19.

A resilient frame is associated with the plait of the material 10, this frame is illustrated per se in Fig. 5, and comprises a pair of parallel flexible members 20 and 21 connected at the ends with elements 22. This frame is so associated with the plait that the flexible member 21 extends through the passage 17 while the flexible member 22 extends through the passage 19. The intermediate layer 13 is formed with openings 23 through which the elements 22 pass so that the construction wherein the flexible members 20 and 21 extend through the passages 17 and 19, is possible. These openings 23 are in the form of slits cut in from the edges of the material. The flexible members 20 and 21 are of lengths substantially identical with the width of the material 10 so as to extend the entire width of the material. The elements 22 extend just within the top and bottom edges of the material 10. Horizontal lines of stitches 24 along the top and bottom edges of the material 10 serve to sew the upper and lower ends of the plait closed so as to hold the frame permanently in position.

A plait of the type described above is adapted

to be used in sport coats, garments in general, and other similar articles. Other material necessarily must be attached to and associated with the material 10 and such material is illustrated 5 on the drawing along the top and bottom edges thereof and indicated by the reference numerals 25. This material is secured down or connected with the material 10 by the stitches 24.

In Figs. 6 and 7 another variation of the invention 10 has been disclosed wherein the material 10' is shown provided with a double plait each half of the plait is substantially identical to the one previously described. This may be readily 15 understood by carefully inspecting Figs. 6 and 7. It should be noticed that the double plait is formed by the rear layers 15 of each of the single plaits as continuations of each other and arranged so 20 that the bends 12 of each single plait are adjacent each other. In other respects this construction is identical to the previous form and similar parts may be recognized by corresponding 25 reference numerals.

In Fig. 8 a modification of the invention has 30 been disclosed to illustrate a feature whereby the resilient frame may be adjusted to accommodate plaits of different sizes. More particularly a resilient frame is shown comprising parallel flexible members 20 and 21 connected at the top and bottom ends by elements 22'. These elements 35 22' are composed of separate sections adjustably connected so as to be capable of holding the side elements 20 and 21 at various adjustable distances. More particularly prongs 26 project 40 from the edge of one of the sections of the element 22' and engage around the other of the sections so as to slidably connect the sections of the element. With this arrangement it is possible to move the parallel flexible members 20 and 21 away from each other or towards each other 45 so as to change the distance between them. This resilient frame may be applied into a plait as previously described relative to the frame illustrated in Fig. 5, the only exception being that this resilient frame may be adjusted to accommodate plaits of different depths.

While I have shown and described the preferred embodiment of my invention, it is to be understood that I do not limit myself to the precise construction herein disclosed and the right 50 is reserved to all changes and modifications coming within the scope of the invention as defined in the appended claims.

Having thus described my invention, what I claim as new and desire to secure by United 55 States Letters Patent is:

1. A plait for sport coats, garments and the like, comprising sheet material formed with a plait extending the entire width and consisting of a front layer continuing with a bend extending 60 the width of the material to an intermediate layer and continuing with a bend also extending the width of the material to a rear layer, a line of stitches securing the front and intermediate layers together near the bend this forming a passage, other stitches securing the intermediate and rear layers together near the bend forming another passage, openings formed in said intermediate layer, and a resilient frame comprising 65 parallel flexible members extending through said passages, and elements connecting the ends of said flexible members and passing through openings in the intermediate layer.

2. A plait for sport coats, garments and the like, comprising sheet material formed with a 70 plait extending the entire width and consisting 75

of a front layer continuing with a bend extending the width of the material to an intermediate layer and continuing with a bend also extending the width of the material to a rear layer, a line of stitches securing the front and intermediate layers together near the bend this forming a passage, other stitches securing the intermediate and rear layers together near the bend forming another passage, openings formed in said intermediate layer, and a resilient frame comprising 10 parallel flexible members extending through said passages, and elements connecting the ends of said flexible members and passing through openings in the intermediate layer, and stitches along the top and bottom of said sheet material for 15 holding the plait closed.

3. A plait for sport coats, garments and the like, comprising sheet material formed with a plait extending the entire width and consisting of a front layer continuing with a bend extending the width of the material to an intermediate layer and continuing with a bend also extending the width of the material to a rear layer, a line of stitches securing the front and intermediate layers together near the bend this forming a 20 passage, other stitches securing the intermediate and rear layers together near the bend forming another passage, openings formed in said intermediate layer, and a resilient frame comprising 25 parallel flexible members extending through said passages, and elements connecting the ends of said flexible members and passing through openings in the intermediate layer, and stitches along the top and bottom of said sheet material for 30 holding the plait closed, said flexible members 35 extending the width of the material and the elements being located immediately within the edges of said material.

4. A plait for sport coats, garments and the like, comprising sheet material formed with a 40 plait extending the entire width and consisting of a front layer continuing with a bend extending the width of the material to an intermediate layer and continuing with a bend also extending the width of the material to a rear layer, a line 45 of stitches securing the front and intermediate layers together near the bend this forming a passage, other stitches securing the intermediate and rear layers together near the bend forming another passage, openings formed in said intermediate layer, and a resilient frame comprising 50 parallel flexible members extending through said passages, and elements connecting the ends of said flexible members and passing through openings in the intermediate layer, and stitches along 55 the top and bottom of said sheet material for holding the plait closed, said latter mentioned stitches being arranged in lines above and below said elements so as to encase the elements.

5. A plait for sport coats, garments and the like, comprising sheet material formed with a plait extending the entire width and consisting of a front layer continuing with a bend extending the width of the material to an intermediate layer and continuing with a bend also extending the width of the material to a rear layer, a line of stitches securing the front and intermediate layers together near the bend, other stitches securing the intermediate and rear layers together near the bend this forming a passage forming another passage, openings formed in said intermediate layer, and a resilient frame comprising 60 parallel flexible members extending through said 65 passages, and elements connecting the ends of said flexible members and passing through open- 70 75

ings in the intermediate layer, and stitches along the top and bottom of said sheet material for holding the plait closed, said openings in the intermediate layer comprising slits extending in from 5 the edges thereof.

6. A plait for sport coats, garments and the like, comprising sheet material formed with a plait extending the entire width and consisting of a front layer continuing with a bend extending 10 the width of the material to an intermediate layer and continuing with a bend also extending the width of the material to a rear layer, a line of stitches securing the front and intermediate layers together near the bend this forming a passage, other stitches securing the intermediate and 15 rear layers together near the bend forming another passage, openings formed in said intermediate layer, and a resilient frame comprising parallel flexible members extending through 20 said passages, and elements connecting the ends of said flexible members and passing through openings in the intermediate layer, and stitches along the top and bottom of said sheet material for holding the plait closed, said elements comprising 25 sections slidably connected with each other, whereby said flexible members may assume various adjustable positions from each other to adapt the resilient frame to plaits of different sizes.

7. A plait for sport coats, garments and the like, comprising sheet material formed with a plait extending the entire width and consisting of a front layer continuing with a bend extending 30 the width of the material to an intermediate layer and continuing with a bend also extending the width of the material to a rear layer, a line of stitches securing the front and intermediate 35 layers together near the bend this forming a

passage, other stitches securing the intermediate and rear layers together near the bend forming another passage, openings formed in said intermediate layer, and a resilient frame comprising parallel flexible members extending through 5 said passages, and elements connecting the ends of said flexible members and passing through openings in the intermediate layer, and stitches along the top and bottom of said sheet material for holding the plait closed, said elements comprising 10 sections slidably connected with each other, whereby said flexible members may assume various adjustable positions from each other to adapt the resilient frame to plaits of different sizes, prongs from one of the sections 15 engaging around the other of the sections to produce a slidable arrangement.

8. A plait for sport coats, garments and the like, comprising sheet material formed with a plait extending the entire width and consisting of a front layer continuing with a bend extending 20 the width of the material to an intermediate layer and continuing with a bend also extending the width of the material to a rear layer, a line of stitches securing the front and intermediate 25 layers together near the bend this forming a passage, other stitches securing the intermediate and rear layers together near the bend forming another passage, openings formed in said intermediate layer, and a resilient frame comprising parallel 30 flexible members extending through said passages, and elements connecting the ends of said flexible members and passing through openings in the intermediate layer, and stitches along the top and bottom of said sheet material for holding 35 the plait closed, said elements comprising sections adjustably connected with each other.
